CIRCUIT BREAKER UNIT

Edward A. Vogel, Beloit, Wis., assignor to Fairbanks, Morse & Co., Chicago, Ill., a corporation of Illinois

Application March 7, 1949, Serial No. 80,035

5 Claims. (Cl. 200—30)

1

This invention relates to improvements in circuit breakers for ignition magnetos and the like, and has reference more particularly to an improved circuit breaker contact unit of cartridge character.

In magneto type ignition systems generally, long experience has shown that a large proportion of ignition failures is traceable directly to failure of the contacts in the circuit breaker portion of the ignition system. Moreover, in the older and prevailing forms of ignition magnetos, the arrangement of the contact breaker mechanism therein usually is such as to require at least partial dismantling of the magneto in order to expose the contacts for repair or replacement, the latter in many instances requiring unscrewing or otherwise dismantling parts of the contact breaker assembly before repair can be effected. Accordingly, it is the principal purpose of the present invention to provide a circuit breaker contact assembly in cartridge form, constructed and adapted for operative placement in a magneto unit such that in the event of contact failure, the contact cartridge unit may be readily and easily removed and replaced with a new cartridge unit, all without dismantling or otherwise disturbing the remainder of the magneto assembly.

Another object of the invention is to provide a circuit breaker unit of cartridge type, for ignition magnetos and the like, which may be quickly removed upon contact failure and replaced by a like unit, and wherein the unit embodies means for facilitating proper location of the cartridge in the magneto assembly, the cartridge unit thus facilitating ready maintenance of the ignition system and a reduction of servicing costs.

These and other objects and advantages of the invention will appear readily from the following description of a presently preferred embodiment thereof, as such is illustrated in the accompanying drawing, wherein:

Fig. 1 is a longitudinal sectional elevation of the presently improved cartridge type circuit breaker contact assembly;

Fig. 2 is a longitudinal sectional elevation thereof, with the section taken in a plane along line 2—2 in Fig. 1;

Fig. 3 is a view in end elevation at the head end of the cartridge unit;

Fig. 4 is a longitudinal section of the outer casing element of the cartridge;

Fig. 5 is a longitudinal sectional view of a contact carriage member adapted for slidable reception in the casing member of Fig. 4, and

Fig. 6 is a transverse sectional view of the car-

2

tridge assembly, as taken along line 6—6 in Fig. 2.

Referring to the drawing by suitable reference characters, the presently improved circuit breaker contact cartridge includes a generally tubular casing member 10 closed at one end by a circular head member 11 which is enlarged to provide a mounting shoulder 12 which in cartridge assembly, seats upon a portion of the magneto frame (not shown) with the tubular portion 10 extending within the magneto for operative association of the cartridge unit with the usual circuit breaker actuating cam (not shown). Slidably received in the member 10 is a tubular member 14 which has an expanded portion 15 riding in an undercut section 16 of member 10. Displacement of member 14 inwardly of member 10 is limited by shoulder 18, while outward displacement of member 14 is limited by an inturned flange 19 at the open end 20 of member 10, engageable by the end portion 22 of member 14. Member 14 is biased toward the end 20 of the casing member 10, by a suitable compression spring 23 bearing between the inner side of head 11 and the inner end 24 of member 14. The movable contact 26 of the unit is positioned internally of member 14, as on the end wall 24 of the latter, and cooperating with contact 26 is the stationary contact 27. Contact 27 is suitably attached to or formed as a part of a block 28 of conducting material, the block in turn being carried by and preferably embedded in a cylinder member 30 of insulating material, arranged within and embraced by member 14.

As appears in Fig. 1, the cylinder member 30 having a metallic core as constituted by the block 28, is supported in fixed relation to casing 10, as by a rod or pin element 31 seated through the members 28 and 30 and having its head end 32 projecting through a longitudinal slot 34 in slide member 14, and through an opening 35 in a side wall of member 10. The end 32 is sleeved in an insulating collar 36 which projects through openings 35 and 34 as shown in Fig. 1. Similarly, the opposite end 38 of pin 31 extends through a similar longitudinal slot 39 in slide member 14 and through a side wall opening 40 in member 10, with the pin end 38 received in an insulating collar 42 extending through the openings 40 and 39. As shown in Fig. 1, the pin 31 is retained in assembly preferably by a cotter element 43 snapped in place in an annular groove 44 provided at the pin end 38. Thus it will appear that the stationary contact 27 is fully insulated through the collars 36 and 42, as well as the insulating carriage 30, from both the slide member 14 and the casing member 10, this being effected because the latter

two members provide the grounding connection for the movable contact 26. Circuit connection to the stationary contact 27 is made conveniently through the pin 31, as by suitable connection of a magneto primary circuit lead (not shown) to one end of the pin. It is to be noted here that magneto primary circuit connection to contact 27 through pin 31, is made in a manner such as to permit ready removal of the cartridge unit for replacement by a new unit, as in the event of contact failure. The connection for example, may be a coiled, flexible lead having its terminal end screwed or otherwise removably attached to the pin 31 at either of its exposed ends. The flexible lead thus would extend with the cartridge unit on removal of the latter, and thereby become accessible for disconnection from the removed unit and application to the substitute unit. However, a presently preferred form of connection is shown diagrammatically, in Fig. 1, as comprising a spring contact finger 45 which is suitably mounted in the magneto assembly in a position to be engaged by the head end 32 of pin 31, in the magneto assembled position of the contact cartridge unit.

Magneto cam actuation of slide member 14 which carries the movable contact 26, is here effected by a cam follower member 46 having a cam-engageable nose portion 47, the cam follower being fixedly mounted in the end portion 15 of slide member 14, as by the end wall 22 of member 14 in end-engagement with member 46 to hold the same in member 14 against an internal shoulder 48 of the latter. The cam follower is maintained in proper position for cam actuation, by the pin 31 which here prevents angular or rotary movement of the member 14 in the casing or shell 10.

Casing member 10 is provided with diametrically opposite openings 50 which afford through similarly disposed openings 51 in slide member 14, ventilation of the cartridge interior in the region of the contacts 26-27. Further, since these openings are in the region of said contacts, they afford inspection openings, affording a view of the contacts in either open or closed condition.

To facilitate proper location of the cartridge unit in assembly to a magneto, the unit is provided with a locating pin or projection 52 disposed in the region of the head seat 12, for reception in a suitable slot or opening provided in a wall of the magneto (not shown). Through pin 52, the cartridge unit is located such as properly to relate the follower nose element 47 to the magneto cam (not shown).

As shown in Fig. 1, the slide member 14 under the influence of spring 23, is displaced to engage its contact 26 with stationary contact 27. Now upon magneto operation to cause cam lift or displacement of the follower member 46, the latter because of its fixed assembly to slide member 14, thereby effects an inward displacement of the slide member against spring 23, such as to produce an opening of the contacts 26-27. The cycle of contact opening and closing continues in this manner, throughout magneto operation.

The cartridge unit may be retained in assembly to the magneto in any suitable manner. However, it is here preferred to employ a rod-like member 60 curved for reception in a transverse groove 61 in the outer surface of the cartridge head member 12, the ends of member 60 being formed to present eyes 62 for reception of mounting screws or the like. Thus upon removal of member 60, the cartridge unit may be readily re-

moved from its assembly position in the magneto, and replaced by a like unit, this without otherwise disturbing the magneto structure.

Having now described and illustrated a presently preferred embodiment of the invention, what I desire to claim and secure by Letters Patent is:

1. A cam-actuated circuit breaker unit comprising a generally tubular casing, a tubular member slidable longitudinally in the casing, a movable contact carried by the member therein, said member having opposite longitudinal slots, a pin extending transversely of the casing and tubular member through said slots in the latter, and supported by the casing, an element carried by said pin and disposed in said tubular member, a stationary contact on said element for cooperation with said movable contact, a spring constantly biasing said member in the direction to effect engagement of the contacts, and a cam-follower fixed in the member and exposed at one end of the casing for cam actuation to move said member in the direction to effect separation of the contacts.

2. A circuit breaker contact device for an ignition magneto having a breaker operating cam, the device being provided as a separate unit adapted for removable application to the magneto in a position for operation by the magneto breaker operating cam, said unit comprising a tubular casing having a flanged head for mounting the unit in the magneto, a pin carried by the casing and extending transversely therein, an element supported by said pin within the casing, a stationary contact on said element, a tubular member slidable longitudinally in the casing and embracing said element, a movable contact carried by said member therein for cooperation with said stationary contact, a spring between said member and the flanged head of said casing, biasing the member in the direction to effect engagement of said contacts, and a cam-follower fixed in the member and exposed at one end of the casing for cam actuation to move said member in the direction to effect separation of said contacts.

3. A circuit breaker contact device for an ignition magneto having a breaker operating cam, the device being provided as a complete unit separate from the magneto and adapted for removable application thereto in a position for operation by the magneto breaker operating cam, said unit comprising a tubular casing having a flanged head for mounting the unit in the magneto, a cylindrical member of insulating material having a metallic core therein, a pin extending transversely through said member and the core thereof and having its ends supported in wall portions of said casing, said pin supporting said member substantially centrally within the casing, a stationary contact carried by the metallic core of said member, a tubular member slidable in said casing and sleeved over said cylindrical member, the tubular member having slots therein receiving said pin therethrough, a movable contact carried by the tubular member therein, for cooperation with said stationary contact, a spring biasing said tubular member in the direction to effect engagement of said contacts, and a cam-follower on the tubular member and exposed at one end of the casing for cam actuation to move the tubular member in the direction to effect separation of said contacts.

4. A circuit breaker contact device in accordance with claim 3, characterized further by

means insulating said pin from the casing and said tubular member.

5. A circuit breaker contact device in accordance with claim 3, characterized further by a projection on the casing adjacent said flanged head thereof, serving in the application of the unit to the magneto, to locate the unit in proper position for cam engagement with the cam-follower of the unit.

EDWARD A. VOGEL.
